UNITED STATES PATENT OFFICE.

HOWARD SMITH, OF DETROIT, MICHIGAN, ASSIGNOR TO MCCORD MANUFACTURING COMPANY, OF CHICAGO, ILLINOIS, A CORPORATION OF MAINE.

FORCE-FEED LUBRICATOR.

1,132,627.

Specification of Letters Patent. Patented Mar. 23, 1915.

Application filed March 21, 1914. Serial No. 826,216.

To all whom it may concern:

Be it known that I, HOWARD SMITH, a citizen of the United States, residing at Detroit, in the county of Wayne and State of Michigan, have invented certain new and useful Improvements in Forced-Feed Lubricators; and I do hereby declare the following to be a full, clear, and exact description of the invention, such as will enable others skilled in the art to which it appertains to make and use the same.

My invention relates broadly to fluid distributors, and more especially to forced feed lubricators; and has for its object to provide an efficient pump of extremely simple structure, adapted to pump a predetermined charge of oil, variable at will, first from the reservoir or other source to the sight-feed well, and then back to the pump and out, through the final delivery pipe, to the bearing to be lubricated, or other point desired.

To these ends, my invention consists of the novel devices and combinations of devices hereinafter described and pointed out in the claims.

The invention is illustrated in the accompanying drawings, wherein like notations refer to like parts throughout the several views.

In said drawings, Figure 1 is a vertical longitudinal section, taken lengthwise of the pump and the casting which carries the same, removed from the reservoir, and showing the movable elements in what may be regarded as their normal positions, with some parts shown in elevation and some broken away; Figs. 2 and 3 are similar views of the same parts, but showing the movable elements in different positions, for comparison with each other and with Fig. 1; Fig. 4 is a vertical section through the oil reservoir, parallel to one of the pumps, with some parts broken away; Fig. 5 is a plan view of one of the pumps detached, with some parts broken away and others shown in section; Fig. 6 is a view of the parts shown in Fig. 5, partly in elevation and partly in vertical section on the irregular or broken line $x^6 x^6$ of Fig. 5; Fig. 7 is a detail, affording a plan view of the finger piece of the angularly adjustable intercepting stop, for the pump piston, and its gage plate; Fig. 8 is a detail in plan, showing slotted guide bracket for stop pin carried

by the stem head of the pump piston; and Fig. 9 is a section through the valve and its seat on the line $x^9 x^9$ of Figs. 1, 2 and 3.

The numeral 1 (Fig. 4) represents the oil reservoir, and 2 its cover or cover section, as the case may be.

The numeral 3 represents a casting fixed to and depending from the cover section 2, within the oil reservoir 1, when the parts are in proper working position.

The numeral 4 represents a shaft having its bearings in the casting 3, and having fixed thereto a worm gear 5, which, when the parts are in working position, engages with a worm 6 fixed to a shaft 7 mounted in the walls of the reservoir 1, and having on its exterior projecting end a pulley 8 for the application of power in the customary way.

The casting 3 is of suitable form to afford a sight-feed well 9 and a valve seat 10. This valve seat 10 is open, at its opposite ends, and is fitted with a combined slide valve and cylinder; or, in other words, the slide valve 11 is suitably recessed to afford a pump cylinder 12. In the cylinder 12 of said slide valve 11 is mounted a pump piston 13, the stem of which passes out through a stuffing box 14, at the inner or right hand end of the said combined cylinder and valve. The stem of said pump piston 13 has removably secured thereto a stem head 15, having, at its inner end, an annular stop flange 16, and, at its outer end, a stop pin 17 projecting above and below the said head. The shaft 4 is provided with an eccentric 18 fitted with an armed strap 19, the outer end of which is pivotally connected to the outer end of the slide valve 11; and, under the rotation of said shaft 4, said eccentric and armed strap will impart to the combined valve and pump cylinder a constant stroke or degree of travel, in opposite directions, in the valve seat 10.

The numerals 20, 21 and 22 represent parts of a rotary or angularly adjustable intercepting stop for the piston 13 of the pump; and of these elements, the numeral 20 represents the active part of the stop, the numeral 21 its stem seated in the casting 3 and the cover section 2; and the numeral 22 a finger piece fixed to the upper end of the stop stem 21 and having a pointer 23 working over a gage plate 24 on the face of the cover section 2, as best shown in Fig. 7.

A stiff leaf spring 25 encircles the stem 21 of the stop, between the casting 3 and the hub of the active part of the stop 20, which spring serves yieldingly to hold the stop in whatever position it may be set. Said active stopping element 20 is in the form of an inverted segment of a cup, and has two stopping surfaces, one of which, marked with the letter *a*, is the periphery 5 of the cup segment, and the other, marked with the letter *b*, is the interior of the cup flange. The said outer or peripheral stopping surface *a* of said segmental stopping cup 20 is formed on the arc of a true circle 10 struck from the axis of the stop stem 21 as a center, and the other or inner stopping surface *b*, afforded by the inner wall of the cup flange, is eccentric, as best shown in Fig. 5. Said stopping cup 20 is so positioned 15 that its stopping flange works between and stands in the path of the annular flange 16 and the stop pin 17 of the stem head 15 carried by the projecting stem of the pump piston 13; and, hence, it follows 20 that the concentric or outer stopping surface *a* of said stopping cup 20 will always intercept said pump piston, at a constant point in its travel toward the axis of the stop, and may, therefore, properly be called 25 the banking stop surface, and the inner or eccentric stopping surface *b* of said cup 20 will intercept said pump piston, in its travel in the opposite direction, or away from the axis of said stop at different points, to wit, 30 earlier or later, according to the angular adjustment of said stopping cup 20, and may, therefore, properly be called the variable stop surface of the said cup. It further follows, of course, that the amount of 35 the displacement in the pump cylinder, at the opposite ends of the piston 13, will depend upon the angular position in which the stopping cup 20 is set.

The lower end of the stop pin 17, carried 40 at the outer end of the stem head 15 of the pump piston 13, works in a slotted guide bracket 26 (see Fig. 8) fixed to the casting 3, as shown in Figs. 1, 2 and 3, and extending outward therefrom to the full length of 45 the possible travel of the said pin; and, hence, this slotted guide bracket 26 will insure the right line reciprocation of the piston stem head 15 and the pin 17, and, at the same time, prevent any rotary motion thereof. This holding and guiding action of said 50 pin 17 is important to insure the proper precision in the intercepting action of the eccentric or variable stop surface of the stopping cup 20 on the said pin 17 and the pump piston 13.

The casting 3 is tapped by a supply pipe 27 depending therefrom, and shown as having on its lower end an intake screen 28 near the bottom of the reservoir 1 and submerged 55 in the oil *Z*, when the parts are in working

position, as shown in Fig. 4. Said casting 3 is also tapped by a goose neck or dropper pipe 29, leading to the sight well 9, under the glass of the sight-feed housing 30 fixed to the cover section 2. The said casting 3 and cover section 2 are also tapped by the final delivery pipe 31, for directing the oil to the bearing to be lubricated, or other point desired, and which pipe 31 is shown as having below its mouth a spring-held check 75 valve 32, suitably seated in the casting 3.

The valve seat 10 and the combined slide valve 11 and cylinder 12, working in said seat, are provided with two sets of coöperative ports, one set of which, to wit, those marked with the reference letters *c*, *c*¹, *c*² and *c*³, coöperate to enable the inner or right hand end of the pump to draw the oil from the reservoir 1 and force the same to the sight-feed well 9; and the other set of which ports, towit, those marked with the reference letters *d*, *d*¹ and *d*², coöperate to enable the outer or left hand end of the pump to draw the charge of oil from the sight well 9 back into the cylinder of the pump, and to force the same out therefrom and through the final delivery pipe 31 to the bearing to be lubricated, or other point desired. Of the said ports, the port *c* is located in the lower face of the valve seat 10, in line with the supply pipe 27; the port *c*¹ is in the under side of the valve 11, in proper position to coöperate with the port *c*, at the proper time, to admit the oil to the inner end of the pump; and the port *c*² is in the upper wall 100 of the valve 11, and, at the proper time, co-operates with the port *c*³ in the upper face of the seat 10, to permit the charge of oil to be forced out from the inner end of the pump through the said ports and the dropper pipe 29 into the sight-feed well 9. The port *d* is a long duct-like port, bored in the casting 3 and leading from the sight-feed well 9 to the upper face of the valve seat 10, as can be understood by comparing the dotted line 110 showing of Figs. 1, 2 and 3 with the full line showing of Fig. 9; the port *d*¹ is in the upper wall of the slide valve 11, in position to coöperate with said long port or duct *d*, at the proper time, to permit the pump to draw therethrough the charge of oil from the sight well 9 into the outer end of the pump cylinder; and the port *d*² is located in the valve seat 10, in proper position to coöperate with the port *d*¹ of the valve 11, at the proper time, to permit the pump to force the oil from the outer end of the pump, through the said ports *d*¹ and *d*², and into the final delivery pipe 31 past the spring-seated check valve 32. With these stated relations of these two different sets of ports in mind, the cycle of actions can be readily traced.

Operation: Assume that the movable elements are in the position shown in Fig. 1, to- 130

wit, that the combined slide valve 11 and cylinder 12, together with the pump piston 13 carried thereby, are all at the right hand or inner limit of their travel toward the axis of the stopping cup 20, with the annular flange 16 of the piston stem head 15 abutting the outer or banking surface *a* of said cup; and that the inner end of the pump contains a charge of oil just previously drawn in from the reservoir. Then, under the continued rotation of the shaft 4, the eccentric 18 and its armed strap 19 will move the combined valve and cylinder outward to the left hand limit of their travel, or away from the axis of the stopping cup 20; and the pump piston 13 will be carried with the combined valve and cylinder until the stop pin 17 of its stem head 15 comes in contact with the inner or eccentric stop surface *b* of said cup 20, whereupon the piston 13 will be intercepted while the combined valve and cylinder continue to move outward to their limit, or until they reach a point a little beyond the position shown in Fig. 2, and thereby the inner end of the cylinder 12 will be moved toward the inner end of the piston 13, at a time when the ports *c*² and *c*³ are in communication, and the charge of oil will be forced from the inner end of the pump out through said ports and the dropper pipe 29 to the sight-feed well 9, and the outer end of the cylinder 12 will, in the same period, be moved away from the outer end of the piston 13, and under the displacement thereby produced, the charge of oil will be drawn from the sight well 9, through the ports *d* and *d*¹, then in communication, into the outer end of the pump. Then, under the continued rotation of the shaft 4, the eccentric and its armed strap will begin to move the combined valve and cylinder toward the right or inward toward the axis of the stopping cup 20, and will carry the piston 13 with the valve and cylinder until the stop flange 16 of its stem head 15 strikes the exterior or banking surface *a* of the stopping cup 20, at which instant the port *d*¹ of the valve will be in communication with the port *d*² of the seat and the final delivery pipe 31, as shown in Fig. 3; and, under the continued inward movement of the combined valve and cylinder, the charge in the outer end of the pump will be forced outward, through the ports *d*¹ and *d*² and the final delivery pipe 31, to the bearing to be lubricated; and, at the same time, displacement will be occurring between the inner end of the cylinder and the inner end of the piston, while the intake ports *c* and *c*¹ are in communication with each other; and, hence, a new charge will be sucked in from the reservoir, while the combined valve and cylinder is moving from the position shown in Fig. 3 into the position shown in Fig. 1, which was assumed as the starting point for tracing the

cycle of actions. Of course, it will be understood that all the members of said sets of ports must be accurately located, and that the valve must have the requisite lap or lead, or both, to insure the coöperation of these port members with the needed nicety to insure the desired predetermined charge of oil.

In the drawings, the stopping cup 20 is shown set to secure a maximum charge of oil; or, in other words, so that its inner or eccentric stopping surface *b* will intercept the pump piston at the earliest point, in its possible outward travel, with the combined valve and cylinder, away from the axis of the stop. By setting the said stopping cup 20 in its other extreme position, a minimum displacement may be secured in the pump, and, hence, a minimum charge of oil can be drawn in and handled thereby; and, if the said stopping cup 20 be set in any one of its possible intermediate positions, an intermediate amount of displacement can be had in the pump, and thus any desired charge of oil be drawn in and handled thereby. Inasmuch as the eccentric stop surface *b* or inner wall of the stopping cup 20 varies on a continuous curve, from its smallest to its greatest eccentricity, it, of course, follows that an extremely fine graduation of the pump displacement, and, hence, in the charge of oil, is available therefrom. This is a matter of large importance, in the usage of this class of lubricators; for it is well known that the range in sizes of charge should be considerable and the graduation fine, in order to adapt the same lubricator to different sizes and kinds of bearings. This pump meets all these conditions, and is, at the same time, reliable. It will be noted, for example, that it has no check valves of any sort within the pump proper; and, hence, its actions cannot be interfered with by sediment or other foreign substances. The efficiency of this pump, for the purposes had in view, has been demonstrated by considerable practical usage thereof. It should be noted that the pump will work equally well regardless of the direction or rotation of the shaft 4. In other words, the pump can be reversed without throwing any of the coöperative elements of the pump out of time.

Of course, it will be understood that, while only a single pump has been illustrated, any desired number might be placed side by side in the same reservoir and be actuated from a common shaft. It should also, perhaps, be noted that the pump shown is removable with the cover section shown, without disturbance of any of the working parts carried by the reservoir; and that, if a series or bank of pumps were employed, they would all be supported from the reservoir cover and be removable therewith.

The construction can, of course, be changed in detail, without departing from the spirit of my invention.

What I claim is:—

- 5 1. The combination with a sight-feed well and pump-actuating mechanism, of a double-acting single cylinder and single piston pump, and positive single means to uniformly vary the displacement between both 10 of the opposite ends of said piston and cylinder, whereby a predetermined charge of fluid, variable at will, may be first pumped from source to said sight-feed well, and thence to the point of final delivery, by the 15 opposite ends of said pump, substantially as described.
- 20 2. The combination with a sight-feed well and a valve seat, of a combined valve and pump cylinder, having a constant travel in said seat, a pump piston carried by the cylinder of said valve, an adjustable intercepting stop for said piston, and two sets of co-operating ports in said valve and seat, whereby a predetermined charge, variable 25 at will, may be first drawn from source to said sight-feed well, by one end of said pump, and then be drawn back into the cylinder and forced out to the point of final delivery, by the opposite end of said pump, 30 substantially as described.
- 35 3. The combination with a sight-feed well and a valve seat, of a combined valve and pump cylinder, having a constant travel in said seat, a pump piston carried by the cylinder of said valve, an adjustable stop having two stop surfaces, one constant and the other variable, for intercepting the piston in opposite directions of its travel, and two sets of co-operating ports in said valve and 40 seat, whereby said single pump is made double-acting to pump a predetermined charge, variable at will, from source to said well, and thence out to the point of final delivery, substantially as described.
- 45 4. In a lubricator, the combination with a reservoir and cover for the same, of a casting fixed to and depending from said cover into the reservoir, and affording a sight-feed well and a valve seat, and a double-act-

ing, single cylinder and single piston pump 50 comprising a combined valve and pump cylinder movable in said seat, an eccentric-bearing shaft mounted in said casting, an armed strap fitted to said eccentric and pivotally connected to the outer end of said 55 combined valve and cylinder, and imparting a constant stroke thereto, a pump piston carried by the cylinder of said valve, an adjustable stop for intercepting said piston, and two sets of co-operating ports in said 60 valve and valve seat, arranged to co-operate substantially as described and for the purposes set forth.

5. In a lubricator, the combination with a reservoir and a cover for the same, of a 65 casting, affording a sight-feed well and a valve seat, depending from said cover, and a double-acting, single cylinder and single piston pump comprising a combined valve and pump cylinder movable in said seat, 70 means carried by said casting for imparting a constant travel to said combined valve and cylinder, a pump piston carried by the cylinder of said valve, an adjustable stop for said piston provided with means for adjusting the same from the exterior of said reservoir, and two sets of co-operating ports in 75 said valve and valve seat, arranged to co-operate substantially as described and for the purposes set forth.

6. The combination with a valve seat, of a combined valve and cylinder, having a constant travel in said seat, a piston carried in the cylinder of said valve, and having a stem head with stop pin, an adjustable intercepting stop for said piston, engageable with said stop pin, and a guide for said stop pin serving to insure the right line motion of said pin, and to prevent rotary movement of said pin and piston, substantially as described.

In testimony whereof I affix my signature in presence of two witnesses.

HOWARD SMITH.
